LINE-UP PLATEN

Joseph Zalkind, New York, N. Y.

Application March 20, 1943, Serial No. 479,954

3 Claims. (Cl. 282—29)

This invention relates to pegging and aligning devices and more particularly to recording devices which facilitate the simultaneous registration of facts and figures upon a number of related record forms thus eliminating duplication of effort when preparing such forms.

In certain instances concerning wage and hour regulations, production cost control systems, etc., Federal and State regulations necessitate furnishing all employees with a statement of their gross earnings and deductions. In the preparation of such records at least four separate writings have heretofore been required upon as many forms. With the device described in the present invention these four or more separate writing operations are reduced to one single writing operation.

The essential portions of the aligning device consist of a flat writing platen with multiple engaging aligning units. The basic form is first inserted into registered position. Additional related forms, of different sizes if desired, are then placed upon a secondary aligning unit and pegged for simultaneous posting and recording of the various forms. The writing in this instance is done by hand. The special advantage of this operation is that related forms can thus be placed together in perfect registration, regardless of the size of the forms which are placed deliberately in varied individual positions upon the aligning platen.

One object of this invention is to provide an aligning device to facilitate the registration of various forms upon a writing platen.

Another object of this invention is to provide a pair of separate pegging units to facilitate the registration of various related forms upon the writing platen.

A third object of this invention is to provide a finger lift to facilitate the simultaneous lifting of either or both of the separate pegging units upon the writing platen.

An additional object of this invention is to provide a separate finger lift to facilitate the lifting of only one of said pegging units above the writing platen.

A further object of this invention is to provide a line finder to facilitate the finding of lined positions upon the basic form and allowing the alignment of check forms with said form.

Further objects will appear from the following detailed specification and the accompanying drawings. Referring to the drawings:

Fig. 1 is a perspective view showing the platen and the manner in which various forms are at-

tached to said platen by means of the pegging aligning units forming a part thereof.

Fig. 2 is a side view of the writing platen shown in Fig. 1.

Fig. 3 is a plan view of the writing platen showing the manner in which the basic record form is placed and is attached upon the platen by means of one of the pegging units.

Fig. 4 is a similar view shown in Fig. 3, showing the manner in which a secondary form is placed upon the writing platen by the other aligning and pegging unit.

Fig. 5 is a similar view shown in Figs. 3 and 4 showing the manner in which a third form is placed and is held upon the writing platen.

Fig. 6 is a section taken on the line 6—6 of Fig. 1 showing constructional details of the pegging unit upon the writing platen. This view shows the pegging unit as it is preliminary to a pegging operation.

Fig. 7 is a similar section as shown in Fig. 6 showing the position of the basic record form after being placed upon the writing platen and being pegged and held in position by the first pegging unit. It also illustrates the manner in which a secondary form is placed for alignment upon the basic form which already had been attached upon the writing platen.

Fig. 8 is a similar view as shown in Figs. 6 and 7 showing the manner in which the secondary form is pegged upon the basic form located upon the writing platen by the operation of the secondary finger lift.

Fig. 9 is a similar view as shown in Figs. 6, 7 and 8 showing the manner in which the first finger lift is operated to raise both pegging and aligning units when it is required to release the forms from the writing platen.

Fig. 10 is a plan view of one end of the writing platen showing the manner in which the pegging and aligning units are attached to the device.

Fig. 11 is a detailed section taken on the line 11—11 of Fig. 2 showing the construction of the secondary pegging and aligning unit.

Fig. 12 is a side view of the pegging and aligning units shown in Fig. 1.

Fig. 13 is a modification of the writing platen shown in Fig. 1, showing a secondary pegging and aligning unit attached to the opposite end of the writing platen.

Fig. 14 illustrates one kind of a check and record sheet combination used in conjunction with a basic form and another record form utilized on the writing platen.

Fig. 15 illustrates a secondary check and record

sheet combination utilized with the writing platen. In this instant a pay envelope is attached to the record sheet.

Fig. 16 illustrates the manner in which the check or pay envelope and record sheet shown in Figs. 14 and 15 are placed upon the writing platen preliminary to writing upon the forms attached thereto.

Fig. 17 is a perspective view of the writing platen shown in Fig. 1 also showing the manner in which a line finder is utilized in conjunction with the check and record form combination.

Fig. 18 is a perspective view of the line finder shown in Fig. 17.

Fig. 19 is a section taken on the line 19-19 of Fig. 18.

Fig. 20 is showing the manner in which the line finder shown in Figs. 17, 18 and 19 is attached to the writing platen by the medium of a rod. In this case the line-finder is moved up and down the writing platen and can be hinged sideways.

Referring to Fig. 1, 20 designates the writing platen proper which consists of a platen 21 having upon one of its ends attached thereto a pegging unit 22. The pegging unit 22, which also serves as an aligning unit, comprises a flat base 23 preferably made out of sheet metal. On either ends of the base 23 there are hinge members 24 and 25 respectively. A hingeing angle-shaped arm 26 and 27 is hinged to the hinges 24 and 25 through the medium of a hinge pin 24a. (see Fig. 10 and Fig. 12). The hingeing arms 26 and 27 are attached upon an elongated crossbar 28 which is a secondary pegging and aligning unit. The arms 26 and 27 are under the influence of a pair of coil springs 29 located upon the pins 24a of either one of the hinges 24 and 25.

The pegging unit proper 30 is placed under an upturned portion 31 of the base 23 while the other end thereof 33 has an under bent 34 which carries a number of sharp pegs 33a fitting within openings 33b upon the writing platen.

The base 23 has a bend 35 which serves as a stop against which the basic form 42 is shoved while the crossbar 28 is somewhat deformed downwardly at 36 and is aligned with a shallow groove 36a upon the writing platen 21. The portion 36 of the crossbar 28 has a tendency of pressing the margin of the basic form 42 within the groove 36a to prevent said form of disengaging with the writing platen.

To operate the pegging unit 22, a finger lift 37 is attached to a hinge extension 38 upon the pegging bar or unit 30 and a spring shaped member 39 one end 40 being inserted under the upturned portion 31 of the base 23 and the other end 41 being attached to the crossbar 28. The end 41 also serves as a secondary finger lift when it is required to raise the crossbar 28 alone and independently of the pegging unit 30 (see Fig. 8).

Referring to Fig. 17, it illustrates the manner a line finder 50 is used in conjunction with the writing platen. The line-finder 50 has a pair of formed extension guides 51 which are fitted within a guide groove 21a upon the writing platen 21. A set of holders 52 are located upon the line-finder 50 and placed in such a manner as to allow the check and record form combination 44 to be held within said holders when it is required to align the check 44 with any of the lines upon the basic form 42. A pointer 53 on the line-finder 50 is used to help find the correct number upon the basic form 42, when lining up related forms with said basic form.

In reference to Fig. 20, it can be seen that in

this case the line finder 50 has a round hollow portion 54 which is fitted upon a bar 55 that is held to the writing platen 21 by a pair of supports 56 on either side, top and bottom, of the writing platen. A finger rest 57 is also located upon the line finder 50 to allow the operator to place his finger to when moving the line-finder 50 upon the writing platen 21.

To operate the writing platen, a basic form 42 is first placed upon the device and is shoved against the guide 35 of the base 22. In this instance the finger lift 37 is depressed all the way down as shown in Fig. 9 thus raising both, the pegging unit 30 and the secondary pegging and aligning unit 28 above the surface of the writing platen 21 and allowing the basic form 42 to be inserted under the first pegging unit and the secondary pegging unit. Once the basic form 42 is in position the finger lift 37 is released thus allowing the first pegging unit 30 to descend upon the margin of the basic form 42 and hold same in place (see Figs. 7 and 8). After placing a carbon paper 43 upon the basic form 42 (see Fig. 4) a check and record slip combination 44 as shown in Fig. 14 is placed upon the platen 21. It can be seen that the basic form 42 (see Fig. 3) is ruled into separate lines which are numbered consecutively in this instance from 1 to 27, although more or less ruled lines can be printed upon the basic form 42. When placing the check 44 upon the platen 21 a lined portion upon the check 44 is aligned with any one of the numbers upon the basic form 42. Upon completion of the registration, the secondary finger lift 41 is raised by the operator (see Fig. 8) until the margin M of the check 44 clears the end 36 of the secondary pegging and aligning bar 28. When the margin M will lay flat upon the platen 21 the finger lift 41 is released to fall upon the portion of the check 44 under the secondary pegging bar 28 to hold it in pegged position.

In Fig. 14 it can be seen that the check 44 comprises a sheet of paper C which is the blank of the check proper and a secondary sheet of paper R which is a record form both being attached or laminated to each other at 44b. A pair of carbon sheets, B and B', are also laminated to the check at 44b. Both carbons are of the same width but the carbon B is longer than the carbon B'. While the carbon B extends over the whole length of the record form R, the carbon B' is only long enough to fit over the record form R and under the length of the check 44.

Once the check 44 is in place, a related earnings record form 47 (see Fig. 5) which is also divided into lined portions which are numbered from 1 to 27, is aligned by the operator with any one of the numbers upon the basic form 42 as is desired. The outer margin M' of the related form 47 is placed upon the upper portion of the secondary pegging and aligning unit 28 until the alignment with the numbers of the basic form 42 has been accomplished. Then the bar 28 is moved upwards by the operator upon the finger lift 41 in the similar fashion as described for the check 44 and shown in Fig. 8.

In this particular instance as shown in the drawings and described in the specification only one set of four related records are made simultaneously including the basic form, the check, the record form and the earnings record form. It is understood that many more forms can be used if it is so desired. Once all the related forms are pegged in position and are correctly aligned with the lined and numbered divisions

upon the basic form 42, the operator is ready to record facts and figures upon the forms attached to the platen. It can be clearly seen that the records made upon the earnings record form 47 will be recorded also upon the basic form 42 and the record form R of the check 44 due to the use of papers (carbon papers) 43, B and B'. After all the writing upon the various forms has been done, the finger lift 37 is depressed and the forms removed allowing the writing platen to be used again and again. 10

In reference to modification shown in Fig. 13, the writing platen shown is utilized in similar manner as described for Fig. 1. In the latter case two pegging and aligning units 22 are used instead of one as shown in Fig. 1, otherwise the 15 operation of the device shown in Fig. 13 is similar to the device shown in Fig. 1 to Fig. 12 inclusive.

In regard to the line finder shown in Figs. 17 to 20, it is used when it is desired to locate the position of the check 44 upon the writing platen. The finger rest 57 is moved upon the writing platen by sliding same with the index finger. 20

The foregoing detailed description of the writing platen has been given for clearness of understanding only and no unnecessary limitations should be understood therefrom, but it should be construed as broadly as permissible in view of the prior art. 25

The writing platen herein illustrated and described is confined to certain structural details. I do not wish to limit myself to such details, but desire to cover all forms and arrangements, being only limited by the scope of the appending claims. 30

Having now described my invention what I claim is:

1. A platen for aligning printed forms including a pair of pegging units hingeably attached thereto, each one of said pegging units in said pair comprising an elongated bar, the first of said bars in said pair being secured to a pair of levers, coil springs included and acting against said levers, said levers being hinged at both ends thereof to said platen, the other elongated bar in said pair being hingeably held thereto and having a substantially rigid finger lift for raising said pegging unit above said platen; said rigid finger lift being securely held to said secondary bar, a secondary finger lift also included for raising the first elongated bar in said pair, said secondary finger lift being located above and over said

rigid finger lift, said secondary finger lift having an arch-shape formation and acting as a spring, one end of said arch being secured to the middle portion of said first bar the other end being secured to said secondary bar; the lifting operation upon said secondary finger lift facilitating the raising of the first bar, and the lifting operation of said rigid finger lift facilitating the raising of both of said bars in said pair of pegging units above said platen for allowing the insertion of printed forms under the bars aforesaid. 5

2. A platen of the class described for aligning printed forms including a pair of pegging units for pegging said forms upon said platen, said pegging units comprising a pair of elongated bars, a pair of levers included, one end of each of said levers being attached to the extreme end of one of said bars in said pair, the other end of said levers forming a hinge and being hinged at both ends thereof to said platen, and being under the influence of a pair of springs included in said platen; a substantially rigid finger lift also included for raising both of said pegging units above said platen for allowing the insertion of printed forms under said pegging bars, and a secondary finger lift for raising only one of said pair of bars; said secondary finger lift being bent in an arc and being positioned above rigid finger lift, said secondary finger lift comprising a flat spring member one end thereof being attached to the middle portion of one said bar the other end to the other bar in said pair. 20

3. A platen for aligning printed forms or the like including a pair of pegging units hingeably held thereon, said pegging units comprising a pair of elongated bars and being U-shaped in cross section; a finger lift included for raising both of said bars, said finger lift comprising a square-shaped wire loop; a secondary finger lift also included for raising only one of said pair of units above said platen, said secondary finger lift comprising a flat elongated member and being bent in an arc, one end of said arc being held to the middle portion of one bar and the other end to the middle portion of the other, said flat member passing between said loop of said finger lift, said member acting as a spring, the spring action of said secondary member facilitating the pegging down and holding of said forms under said pegging units. 35 45 50

JOSEPH ZALKIND.
